UNITED STATES PATENT OFFICE.

PERRY D. MARTINDALE, OF PONTIAC, MICHIGAN.

IRONING-BOARD.

1,337,936.

Specification of Letters Patent. Patented Apr. 20, 1920.

Application filed November 17, 1917. Serial No. 202,585.

To all whom it may concern:

Be it known that I, PERRY D. MARTINDALE, a citizen of the United States, residing at Pontiac, in the county of Oakland and State of Michigan, have invented new and useful Improvements in Ironing-Boards, of which the following is a specification.

This invention has reference to ironing boards.

In carrying out my invention, it is my purpose to produce, as a new article of manufacture, an ironing board comprising a wooden frame and a metal top or facing for said frame. In the ironing of certain class of materials, a substantially non-yielding surface is desirable, in order to obtain the proper effect on the material or garment, while in other materials a yielding effect is desirable between the board and the said material. To accommodate the last referred to materials, which, it may be stated, are more common, and consequently, require more frequent ironing than the first referred to materials, the ironing wooden board has arranged thereon a pad and a facing for the pad. From experience, I have found that while such arrangement permits of a partial yielding between the material ironed and the board, the pad, incident to the iron passing thereover and the contact of the iron point therewith, becomes rumpled at places and smooth in other places so that the same can not be considered long lived, nor thoroughly effective for the purpose intended. With my improved construction of boards, the wooden frame is, at portions thereof, sufficiently widened to receive thereon articles of the class first mentioned, while the metallic facing is sufficiently yieldable to impart a desired resiliency between the last mentioned articles and this portion of the board.

It is a further object of my invention to produce an ironing board which shall be comparatively cheap in manufacture, in which the leg for supporting the board is telescopic and is provided with a hooked end to engage with the edge of a table and other support, and also in which the board has loosely secured to one of its sides a flexible element, the free end of the said element having a hook thereon and the other side of the board having an eye to receive the hook of the flexible element, and whereby the said flexible element may be brought

to engage with the edges of the fabric covering for the board.

Other objects and advantages will appear as the nature of the invention is more fully understood, reference being had to the accompanying drawings, in which,

Figure 1 is a perspective view of the improved ironing board illustrating the same arranged upon a support.

Fig. 2 is an approximately central longitudinal sectional view through the same.

Fig. 3 is a bottom plan view, the leg being in its folded position.

Fig. 4 is a transverse sectional view approximately on the line 4—4 of Fig. 3.

Fig. 5 is a horizontal sectional view approximately on the line 5—5 of Fig. 4.

Fig. 6 is a perspective view of the detachable shelf which may be employed.

My improved construction of ironing boards includes a wooden frame 10 and a metallic facing or top 11 for the frame. The frame 10 comprises parallel side members 12 respectively, which have their outer ends beveled as at 13. These beveled ends 13 are engaged by oppositely beveled surfaces upon the outer end members 14 of the frame. The members 14 incline toward each other and meet at the center of the frame, the members 12 and 14 being secured together in any desired or preferred manner. The frame is centrally provided with a brace 15, the outer ends of the same being beveled in opposite directions to contact with the inner inclined surfaces of the end members 13, and the brace is of a length equaling the length of the frame and board proper. The sides 12 as well as the central brace member 15, adjacent what I will term the outer end of the board are cut upon their upper surfaces to provide substantially rectangular depressions which enter from the ends of the said members, and in these depressions is arranged a transverse wooden member or board 16 that is secured to the side and brace members and has its outer face flush with the outer surfaces of the said side and brace members. This board 16, together with the other elements comprising the frame 10, constitute the rigid or non-yielding portions of the board, and the metallic top or facing 11, at the portions thereof outward of the board and between the other elements comprising the frame 10 constitutes the yielding or resilient portion of the board. By reference to the draw-

100
105

ings, it will be noted that the metallic facing 11 is shaped to correspond with the shape of the frame and has its edges bent over and secured to the frame as indicated by 5 the numeral 17.

The side and what I have termed the outer end members of the frame are provided with a continuous groove 18, the said groove being located below the edge 10 of the bent portion 17 of the metallic member 11. In this groove 18, adjacent what I have termed the inner end of the board, and on one side of the said board is secured, as at 19, a flexible element 20. The element 15 20 is preferably in the nature of a coil spring and has its free end provided with a hook 21. In the groove, to the side of the board diametrically opposite that to which the flexible element 20 is loosely connected, 20 (at 19), is arranged an eye 22, and this eye is designed to receive the hook 21 of the element 20 when the same is brought around the board in the groove, the flexible element 20 being designed to secure the cloth or 25 covering 23 upon the board.

The central member or brace 15 and the board or rectangular wooden plate member 16 are provided with alining slots 24, entering from the outer end of the board. Secured 30 upon the under face of the brace member 15 nearer the terminal of the slot 24 are eye members 25, the same providing bearings for a shaft in the nature of a bolt 26, the said bolt being engaged by a nut 27, and 35 this bolt passes freely through an opening provided in the upper element 28 of the leg or support 29. The element 28 is of a width to freely pass through the slot 24 and has its outer end hook shape as at 30. The 40 inner end of the element 28 is hollow and receives therein the outer member 31 for the leg 29, a binding element 32 being adjustably connected to the upper leg section 28 and contacting with the lower leg section, 45 retains the said lower leg section properly adjusted with respect to the upper

section. As disclosed in Fig. 1 of the drawings, the hook shaped end of the leg is designed to be arranged over the top of a support, such as a table 33 and the inner or 50 rear edge of the board is designed to be arranged below the said edge of the table 33, the leg section contacting with the floor on which the table rests effectively holding the hook in engagement with the table supporting the board thereon. 55

One of the sides of the improved ironing board, adjacent the rear end thereof, is preferably provided with transverse orifices 34 designed to receive the inturned or 60 angular ends 35 of arms 36, the said arms having their upper portions bent in the same direction as the ends 35 and received in the rounded edges of a shelf 37. This shelf may be readily attached to or removed 65 from the board and when in attached position may serve as an iron holder, a holder for the wax, or for other desirable purposes.

Having thus described the invention, what 70 I claim is:

The herein described construction of ironing boards including a substantially rectangular wooden frame having one of its ends beveled to the sides thereof, a wooden 75 member transversely connecting the sides at the opposite end of the board, and a centrally arranged brace for the frame, a metallic facing provided with flanges on its sides and one end, fitting over the sides and 80 beveled ends of the frame, both the sides and the beveled ends of the flange and frame having a continuous longitudinal groove therethrough, eyes in the groove adjacent to the inner end of the board, and 85 a spring member received in the groove having elements on the ends thereof engaging with the eyes, and said spring member designed to hold a covering cloth on the board. 90

In testimony whereof I affix my signature.
PERRY D. MARTINDALE.
